Filed May 21, 1973, Ser. No. 362,219

Term of patent 3½ years

Int. Cl. D26—05

U.S. Cl. D48—20 E

FIG. 1 is a perspective view of an industrial light fixture, showing my new design.

FIG. 2 is a top view thereof.

FIG. 3 is a front view thereof.

FIG. 4 is a bottom view thereof.

FIG. 5 is a side view taken from the right side of FIGS. 2, 3, and 4.

FIG. 6 is a rear view thereof.

FIG. 7 is another side view taken from the right side of FIGS. 2, 3, and 4 showing the pivotal front shade of the fixture in an extended position.

The brackets are broken away in FIGS. 1, 2, 3, 4 and 6 to indicate indeterminate length.

I claim:

The ornamental design for an industrial light fixture, as shown and described.
